UNITED STATES PATENT OFFICE.

ERNEST R. HUNTLEY, OF LOS ANGELES, CALIFORNIA, ASSIGNOR TO INDUSTRIAL RESEARCH CORPORATION, OF TOLEDO, OHIO, A CORPORATION OF DELAWARE.

ENGINE-STARTING MECHANISM.

Application filed September 9, 1920, Serial No. 409,141. Renewed June 4, 1924.

To all whom it may concern:

Be it known that I, ERNEST R. HUNTLEY, a citizen of the United States, residing at Los Angeles, in the county of Los Angeles 5 and State of California, have invented certain new and useful Improvements in Engine-Starting Mechanism, of which I declare the following to be a full, clear, and exact description.

10 This invention relates to engine starting mechanism. More specifically it relates to means for starting an internal combustion engine by means of an electric motor, where- in a connecting drive is used which auto- 15 matically engages and disengages with the engine before and after the starting of the same.

An object of the invention is to provide a 20 mechanism which starts the engine subsequent to the motor energization without the necessity of any manual movements.

A second object is to supply an automatic starting system wherein positive connection between the motor and driving pinion is en- 25 tirely prevented after the engine has been started.

Another object is to provide a yielding clutch mechanism in which jamming of the clutch elements is made impossible.

30 Still another object is the provision of a drive mechanism wherein the variation of load at starting due to the compression of the engine cylinders is yieldingly absorbed.

Further objects and objects relating to 35 details of construction and economies of manufacture will become apparent from the subsequent description.

In the accompanying drawing Figure I is a longitudinal view of the starting mechanism, with parts in section, and

40 Figure II is a transverse section taken on lines II—II of Figure I and looking in the direction of the arrows.

Referring to the drawings, wherein like 45 numerals refer to like parts, an electric motor 10 is disclosed, having an armature 11, and a hollow shaft 12. The motor casing 13 is formed with flanges 14 at one end which afford means for attaching the motor 50 to the engine adjacent the engine flywheel or equivalent engine gear member. This end of the motor casing has also a protruding central portion 15 which is apertured to receive a bushing 16. The bushings 16 and 17 55 form bearings for the hollow shaft 12, which

in turn is keyed to the motor armature 11 and is rotatable therewith.

Positioned within the hollow shaft is a drive shaft 18 at the drive end of which is fixed a pinion 19 by means of a key 20 and 60 screw nut 21. The engine member 22 has a portion 23 of its rim extended radially in which gear teeth 24 are cut, and this portion 23 is designed to be so positioned relative to the motor and pinion 19 that axial move- 65 ment of the pinion toward the motor will bring about a sliding enmeshment of the gear teeth 24 and 25 of the fly-wheel and pinion respectively, and in order to facilitate this enmeshment the teeth of the pinion 70 are curved as at 26.

As intimated above, the drive shaft is formed for slidable movement within the hollow shaft, and to take care of this function the inner or drive end of the hollow 75 shaft is threaded internally to receive a bushing 27 wherein the shaft 18 has both axial and rotary movement. The inner surface of the bushing is grooved to receive a split ring 28 serving as means for preventing ingress 80 of dirt.

The other or outer end of the drive shaft 18 is formed with a coarse thread 29 which is adapted for movement within a nut 30 loosely mounted for rotary and longitudinal 85 movement within the hollow shaft. The inner end of the nut is formed with a jaw member 31 for a purpose hereinafter disclosed. The outer end of the nut normally has contact with a cylinder 32 screw thread- 90 ed to the hollow shaft 12 at 33 and serving as an outer stop for the axial movement of the nut 30. The outer end of the cylinder carries a plate 34 which is transversely grooved as at 35 to permit proper tool en- 95 gagement. A cupshaped stamping 36 with radially extending flanges 37 underlying the portion 38 of the motor casing serves as a dust protector and seal for the rotatable parts above indicated.

100 Fixed to the drive shaft 18 by means of a pin 39 is a narrow tubing 40, the outer end of which is formed into an element 41 of a jaw clutch and the inner end with a smooth edge 42 abutting the bearing 27 and forming 105 a stop against extended inner movement of the shaft 18.

110 A second tubing 43 is loosely mounted on the drive shaft 18 adjacent the tubing 40 and is secured to the hollow shaft by means

of a split ring 44, riding in corresponding grooves 45 and 46 cut in the tubing and hollow shaft respectively. As indicated at 47, to permit proper assembly the groove 46 has 5 its inner wall formed at a broad angle.

Both ends of the tubing 43 are cut to form 10 jaw clutch elements, the element 48 being designed for connection with the clutch element 41 above mentioned. The clutch element 49 of the tubing 43 is designed for 15 cooperative engagement with the jaw member 31, through a spring 50 which is coiled around the drive shaft and has its inner and outer ends abutting the jaw clutch elements 15 49 and 31 respectively. The spring 50 as shown in Figure II is not circular in cross section but has flattened portions 51 and outstanding portions 52, the latter portions having 20 frictional engagement with the inner wall of the hollow shaft. In addition the spring 50 is slightly under compression so 25 that the nut 30 is held normally at the limits of its outward movement against the stop 32.

The clutch elements 41, 48, 49 and 31 are 30 so formed that a drive connection is maintained when the armature rotates in a counter-clockwise direction looking inward along the shaft toward the pinion.

The operation of the mechanism is as follows: Assuming an energization of the 35 motor, the armature and its hollow shaft having a counter-clockwise rotation, inasmuch as the friction between the tubing 43 and its holding ring and the spring and hollow shaft is material, these parts will rotate the nut 30 with the hollow shaft. The friction on the drive shaft is, on the other hand, slight and its inertia considerable and consequently the drive shaft will screw itself 40 automatically into the nut thereby drawing the pinion into mesh with the engine gear. In the event that the gear teeth meet endwise the nut will be pulled in slightly against the spring until the increased friction causes 45 a partial rotation of the pinion sufficient to clear the teeth when proper enmeshment will ensue.

The clutch elements 41 and 48 have the 50 same pitch approximately as the thread 29 so that when the pinion is in mesh these elements engage with the axial surfaces only of the jaws in contact thereby preventing jamming of the coacting surfaces and consequent difficulty of disengagement.

Immediately on engagement of the clutch elements 41 and 49 there is a tendency to 55 transmit motion from the rotating shaft to the non-rotating drive shaft now held by the engine load. There is therefore a back impulse transmitted to the spring which tends to unwind the same and results, first, in a yielding out movement of the flattened spring sections until complete contact of the spring periphery and hollow shaft is made, and 60 second, in a positive drive between the ho-

low shaft and spring due to the highly increased frictional contact thereinbetween. The motor then starts the engine in the usual way.

When the engine has started, the impulse 70 of the engine gear accelerates the drive shaft sufficiently to cause an unscrewing thereof from the nut and this carries the pinion out of mesh with the engine gear. Immediately after this engine impulse at 75 starting, the load on the spring having been removed, it assumes the normal position. Attention is here directed to the fact that if the engine member while rotating from engine power were to accidentally engage the 80 pinion, the impulse transmitted is identical to the starting impulse and merely tends to wind the spring in a direction to contract the same, thereby tending to completely 85 break down frictional engagement between the drive shaft and hollow shaft and prevent any injurious motion being transmitted to the motor armature.

I am aware that the particular embodiment of my invention herein shown and described is susceptible of considerable variation without departing from the spirit thereof, and I therefore desire to claim my invention broadly as well as specifically as indicated by the appended claims.

I claim as my invention:

1. In a motor starter for engines, in combination an engine member; a motor having a hollow shaft; a drive shaft secured within the hollow shaft and adapted for axial and rotative movement relative thereto; a pinion on one end of the drive shaft adapted for connection with the engine member; a screw thread at the other end of the drive shaft having co-operative engagement with an internally threaded nut mounted within the hollow shaft; a jaw clutch within the hollow shaft concentric with and loosely mounted on the drive shaft; a coiled spring surrounding the drive shaft, the ends of said spring being operatively connected to said clutch and nut respectively; and a clutch member fixed to the drive shaft; said pinion and engine member, clutch members, and spring and hollow shaft being adapted to form automatically a positive driving connection between the motor and the engine member when the motor is initially energized and to disengage automatically when the engine member is driven by the engine.

2. In a drive mechanism, the combination of a driven member, a drive shaft, a pinion fixed to the drive shaft and adapted for movement into engagement with the driven member; a hollow shaft encompassing a portion of said drive shaft; and friction controlled means for inaugurating an initial axial movement and a subsequent rotary movement of said drive shaft.

3. In a starting mechanism for engines,

the combination of an engine member; a hollow shaft; a drive shaft within the hollow shaft; a pinion fixed to one end of the drive shaft and adapted to engage with the engine member; clutch elements within the hollow shaft; and means for moving said clutch elements into operative engagement.

4. In a starting mechanism for engines, the combination of an engine member; a hollow shaft, a drive shaft within the hollow shaft; a pinion fixed to one end of the drive shaft adapted to engage the engine member; a clutch device within the hollow shaft comprising a clutch element fixed to the drive shaft; a double clutch element loosely mounted on the drive shaft for rotary movement relative to said drive shaft and hollow shaft; and a coiled spring surrounding the drive shaft, said spring having a portion of its outer surface in frictional contact with the hollow shaft and one end thereof in engagement with the adjacent jaw of the double clutch element.

5. A motor drive comprising a hollow shaft; a drive shaft having a pinion fixed thereon; a clutch element fixed to the drive shaft; a complementary clutch element loosely mounted on the drive shaft; and a resilient driving connection between said complementary clutch element and hollow shaft.

6. In a starting mechanism for engines, the combination of an engine member; a hollow shaft; a drive shaft having a pinion at one end and a screw thread at the other end, said drive shaft being positioned partially within the hollow shaft; a nut screw

threaded on the threaded portion of the drive shaft, and adapted for both axial and rotary movement relative to the hollow shaft; a stop for limiting axial movement of the nut in one direction; a spring adapted to limit yielding movement of the nut in the opposite direction; and clutch means between the spring and drive shaft for establishing a positive driving connection from the motor to the pinion when the pinion is in engagement with the engine member.

7. A drive mechanism comprising a motor having a hollow shaft; a drive shaft axially slidable and rotatable within said hollow shaft; a pinion fixed to one end of the drive shaft; means for moving the pinion axially into engagement with its load when the motor is started; and yielding frictional means operative to establish a positive driving connection between the motor and pinion subsequent to its engagement with the load.

8. A starting mechanism for engines comprising a motor having a hollow shaft; a drive shaft axially slidable and rotatable within said hollow shaft; a pinion fixed to one end of the drive shaft; means for moving the pinion axially into engagement with its load when the motor is started; and yielding frictional means operative to establish a positive driving connection between the motor and pinion subsequent to its engagement with the load, said frictional means being adapted to break the driving connection when the load is removed therefrom.

In testimony whereof, I affix my signature.

ERNEST R. HUNTLEY.
